(57) **CLAIM**

The ornamental design for a fishing reel, as shown and described.

DESCRIPTION

FIG. 1 is a first perspective view of a first embodiment of a fishing reel that includes a fishing reel portion in accordance with my new design;

FIG. 2 is a second perspective view of a fishing reel that includes a fishing reel in accordance with my new design;

FIG. 3 is a third perspective view of a fishing reel that includes a fishing reel in accordance with my new design;

FIG. 4 is a first side elevational view of the fishing reel illustrated in FIG. 1 that includes the fishing reel;

FIG. 5 is a second side elevational view of the fishing reel illustrated in FIG. 1 that includes the fishing reel portion but in which the fishing reel is completely hidden from sight;

FIG. 6 is a top plan view of the fishing reel illustrated in FIG. 1 that includes the fishing reel;

FIG. 7 is a bottom plan view of the fishing reel illustrated in FIG. 1 that includes the fishing reel;

FIG. 8 is a rear elevational view of the fishing reel illustrated in FIG. 1 that includes the fishing reel;

FIG. 9 is a front elevational view of the fishing reel illustrated in FIG. 1 that includes the fishing reel;

FIG. 10 is an enlarged perspective view, similar to FIG. 1, of the fishing reel illustrated in FIG. 1;

FIG. 11 is an enlarged perspective view, similar to FIG. 2, of the fishing reel illustrated in FIG. 2; and,

FIG. 12 is an enlarged perspective view of a second embodiment of a fishing reel, which is identical to the fishing reel illustrated in FIGS. 1 to 11, except that a selected boundary of the fishing reel is shown in broken lines.

In the drawings, the broken line illustration of the environmental structure (the remaining structure of the fishing reel) in the drawings is not part of the claimed design. In other words, the broken line portion of the fishing reel does not form part of the claimed design. Also, in the drawings, the
